[57] CLAIM

The ornamental design for a plate or similar article, as shown and described.

DESCRIPTION

FIG. 1 is a top plan view of a plate or similar article showing my new design as seen in the direction of arrow I in FIG. 2;

FIG. 2 is a side elevational view thereof; and

FIG. 3 is a bottom plan view thereof as seen in the direction of arrow III in FIG. 2.

The characteristic feature of the design resides in the floral pattern as shown on the upper surface of the plate. The floral pattern is shaded to indicate color contrast.
